[57] CLAIM

The ornamental design of a stand for holding items, as shown and described.

DESCRIPTION

FIG. 1 is a front elevational view of the stand for holding items showing my new design;

FIG. 2 is a side elevational view of FIG. 1;

FIG. 3 is a rear elevational view of FIG. 1;

FIG. 4 is a side elevational view of FIG. 1 illustrating the side opposite that which is shown in FIG. 2;

FIG. 5 is a top plan view of FIG. 1; and,

FIG. 6 is a bottom plan view of FIG. 1.

The characteristic features of my design include the shape and exterior configuration of the stand as shown in the figures described.
